UNITED STATES PATENT OFFICE.

JOHN D. E. DUNCAN, OF BROOKLYN, NEW YORK.

INSULATOR.

No. 830,203.

Specification of Letters Patent.

Patented Feb. 25, 1908.

Application filed September 9, 1907. Serial No. 391,893.

To all whom it may concern:

Be it known that I, JOHN D. E. DUNCAN, a citizen of the United States, and resident of the borough of Brooklyn, county of Kings, and State of New York, have invented a certain new and useful Improvement in Insulators, of which the following is a specification, taken in connection with the accompanying drawings.

10 This invention relates to insulators, and more particularly to high tension insulators such as are required to carry currents of high voltage.

In the accompanying drawings showing 15 illustrative embodiments of this invention, and in which the same reference numerals refer to similar parts in the several figures, Figure 1 is a vertical section through one of the insulators, showing portions of two other insulators connected with it. Fig. 2 is a vertical section similar to Fig. 1 showing a slightly modified construction. Fig. 3 is a bottom view of Fig. 2 looking in the direction of the arrow. Fig. 4 is a detail plan view of the pressure ring shown in Fig. 2. Fig. 5 is a partial horizontal section on line 5—5 of Fig. 2 showing the slot through which the head of the bolt may be passed. Fig. 6 is a detailed sectional view, showing one form of arc ring. Fig. 7 is a vertical section of a modification. Fig. 8 is a side elevation, showing a plurality of my insulators supporting the cable. Fig. 9 is a detailed plan view on line x—y of Fig. 1. Fig. 10 is a detailed sectional view on line s—t of Fig. 1.

In the illustrative embodiments of the invention shown in the drawings, 1 is an insulator having a petticoat 3 and dome 2 which may be made of glass, porcelain or any other 40 suitable insulating material; the diameter of the dome 2 is such as to fit snugly within the mouth 4 of the bell or body portion 5 of the insulator 1. This bell or body portion may be formed of any suitable material, but I prefer- 45 ably form it of cast or malleable iron, and form an inwardly extending rib or flange 6 at or near its mouth 4; two vertically extending arms 7—7 are secured to or cast on the top of the bell 5 between which is located the eye 8 of a bolt 9, the bolt and eye being secured to the arms 7—7 by any suitable means such as a pin 10 which as shown in Fig. 1 passes 50 through openings 11—11 in the arm 7—7 and through the eye 8 of the bolt 9, securely lock-

ing one insulator to the bolt of the next, if a 55 plurality of insulators are to be used.

Within the dome 2 I may locate the dome 12 of a smaller petticoat 13, the diameter of this dome being just sufficient to pass through the throat 14 of the dome 2. I may, 60 however, use only one petticoat and one dome or I may use a plurality of such petti- 65 coats nested one within the other and all sup- ported by the body portion 5. For purposes of illustration I show two such petticoats 5, which I have found in practice to be ample, though my invention, as noted, is not limited to the number of petticoats, sup- 70 ported by each body portion 5.

When two petticoats are used with each body portion I mount within the second pet- 75 ticoat 13, or if more than two are used then from the innermost one, a fastening means which as shown in Fig. 1 is a split bolt 9 having an eye 8 formed by bending the two arms 16—16 of the bolt 9 upon themselves and to this eye 8 I secure another body portion 5 if I desire to use a plurality of insulators, or if I only desire to use one insulator I secure a 80 clamp 17 for supporting the cable 18. (See Fig. 3.) The ends 19—19 of the arms 16—16 are preferably enlarged as shown in Figs. 1 and 9 for a purpose to be hereinafter described.

I assemble my insulator or nest and securely 85 bind the parts together by taking the body portion 5 and placing within it a suitable quantity of binding material such as cement 20, and press the head 21 into the body por- 90 tion 5 as far as possible. The dome 12 is mounted within the hollow dome 2 in ex- 95 actly the same manner, the cement 20 being used to fasten the parts together. The arms 16—16 are forced within the dome 12 by the ends 19—19 being made to yield towards each other until they reach the enlarged 100 chamber 22, which is filled with cement 23, when they spring outwardly, the cement 23 being forced between the arms 16—16 and locking the arms in the position shown in Fig. 1 as soon as the cement is set. That portion of the cement which is forced between the arms 16—16 of course, resists the inward movement of the ends 19—19 and thereby prevents the bolt 9 from being withdrawn 105 from the petticoat 13, the enlarged ends 19—19 coöoperating with the cement and the shoulders 26 to accomplish the same result.

To compensate for the strain upon the bolts and to transmit such strain to the body portion 5, thereby as far as possible taking it from the petticoats, I arrange shoulders 24, 5 25 and 26 upon the flange 6, the dome 2 and the interior surface of the dome 12 respectively. I also preferably arrange complementary shoulders, 50 and 51 upon the exterior surface of the domes 2 and 12 respectively. By this arrangement the strain or weight upon the bolt 15 is readily transmitted to the strengthening flange 6 upon the bell 5, the resultant strain being indicated by lines AB and AC, this action being assisted by the beveled contour of the bolt ends 19; being understood, of course, that after the cement hardens, the strain is transmitted through it and through the respective shoulders 26, 51 and 25, 50 to the shoulder 24 10 of the bell 5. The strain may be also transmitted by a pressure ring 32 shown in dotted lines in this figure, and in section in Fig. 2, though it is to be understood that my invention is not limited to the use of such a 15 pressure ring.

Instead of using the split bolt 9 with the arms 16—16 I may use a solid bolt 27, Fig. 2, having a rectangular head 28, which is adapted to pass through the throat 29 of the small petticoat 30 and then be given a 20 partial revolution to occupy the position shown in dotted lines in Fig. 5, it being preferably locked in this position by any suitable means, such as cement 31. Or I may, 25 (Fig. 7), use a solid bolt 52 having a head 53 which is adapted to snugly pass through the throat 54 of the dome 12, the bolt being held in the recess 55 by any suitable means such as cement 56. To further strengthen 30 the insulator, I may use either with or without cement, a split pressure ring 32, which is shown in detail in Fig. 4, which may consist of four segments, the exterior surface of the ring being provided with a shoulder 33, 35 which is adapted to coöperate with the shoulder 34 of the dome 2; in this form the shoulder is arranged at a sharper angle than in the form shown in Fig. 1.

By using one or a plurality of such insulators, as shown in Fig. 8, for instance, the required surface to prevent leakage and penetration of the insulators may be obtained, dependent upon the voltage to be carried by the cable 18, it being understood 40 of course, that with the higher tension caused by the cable, more insulators should be used. In Fig. 8 I have shown four such insulators but it is to be understood that one or two or more such insulators would come 45 within the terms of my invention. To still further prevent the puncture of the insulators and to prevent serious heating of the insulator petticoats, in case of arcing due to the unusual rise of voltage, and to keep the 50 arc away from the petticoat proper, I may,

but it is understood that my invention is not limited to this construction, mount an arcing ring 35 which as shown in Fig. 3 is split, the ends 36—36 being bent at right angles to the body of the ring and an opening formed in them for the reception of a bolt 37, which by means of a nut 38 will tighten the arcing ring 35, upon the petticoat 3 in an obvious manner as shown in Figs. 2 and 3. To space this ring from the petticoat 3, I may cast or otherwise secure lugs 39 which will contact with the flared end of the petticoat 3. Such an arcing ring may be used alone as shown in Fig. 6, or in conjunction therewith, I may use arcing rods 40 which are secured to the 55 ring by means of rivets 41 or in any other suitable manner. Such a ring alone or in conjunction with the rods will cause the leaking current if of sufficient tension to pass through them rather than to puncture the 60 insulators. By using a sufficient number of my insulators, either one or more, the number being determined by the voltage carried by the cable 18, I am enabled to resist and practically prevent the leaking of the 65 current from the cable 18, to the support (not shown), from which my insulators are suspended. Should, however, a current of higher voltage be sent through the cable 18, than that which it is nominally meant to 70 carry, instead of the excessive potential puncturing and ruining the insulators 1, it is permitted to leak over the insulator through the arcing ring 35 and arcing rods 75 40, if such be used.

Having thus described my invention in connection with the several illustrative embodiments thereof, to the details of which it is not of course, to be limited, what is claimed as new and what is desired to be secured 80 by Letters Patent is set forth in the appended claims.

1. In insulators, a body portion having an inclined internal supporting shoulder, a petticoat having a dome within said body portion, an internal petticoat having an inner dome located within the dome of said outer petticoat, a fastening bolt having a plurality of arms provided with inclined ends in the chamber within said inner dome, there being coöoperating inclined shoulders on said domes to coöperate with said bolt ends and said supporting shoulder and cement locking the parts together and adapted to transmit strain angularly outward through said shoulders to said body portion.

2. In insulators, a body portion having an internal supporting shoulder, a petticoat having a dome within said body portion, an inner petticoat having an inner dome within the dome of said outer petticoat, fastening means provided with an enlarged upper end in the chamber within said inner dome, there being coöoperating inclined shoulders on said domes to coöperate with the end of

- said fastening means and said supporting shoulder and cement locking the parts together and adapted to transmit strain angularly outward through said shoulders to said body.
3. In insulators, a body portion having an internal supporting shoulder, a petticoat having a dome within said body portion, an inner petticoat having an inner dome within the dome of said outer petticoat, a fastening having a flaring end in the chamber within said inner dome, there being coöperating shoulders on said domes to coöperate with the end of said fastening and said supporting shoulder and cement locking the parts together and adapted to transmit strain outward through said shoulders to said body portion.
4. In insulators, a body portion, a petticoat having a dome supported within said body portion, said dome being provided with internal shoulders, a fastening having a plurality of members provided with enlarged portions in the chamber within said dome and coöperating with said shoulders, means to lie between the ends of said members to prevent the withdrawal of said fastening from the insulator and binding material to secure the parts together and to transmit strain angularly outward through said shoulders.
5. In insulators, a body portion, a petticoat having a dome within said body portion, an inner petticoat having an inner dome within the dome of said outer petticoat, a fastening bolt having a plurality of arms provided with flaring portions in the chamber within said inner dome, there being inclined shoulders on said inner dome to coöperate with said flaring portions and binding material locking the parts together and adapted to transmit strain angularly outward through said shoulder to said body portion.
6. In insulators, a body portion, a petticoat having a dome within said body portion, an inner petticoat having an inner dome within the dome of said outer petticoat, fastening means in the chamber within said inner dome, there being inclined coöperating shoulders between said domes, a pressure member between said inclined shoulders and binding material locking the parts together whereby strain is transmitted angularly outward through said shoulders to said body portion.
7. The combination of an insulator and an arcing ring.
8. The combination of an insulator and an arcing ring detachably connected to it.
9. The combination of an insulator, an arcing ring, and arcing rods.
10. The combination of a petticoat insulator having an arcing ring mounted upon it.
11. The combination with a petticoat insulator of a detachable arcing ring and arcing rods mounted upon the ring.
12. In insulators, a body portion, a plurality of petticoats having nested domes within said body portion, a fastening bolt having a plurality of arms provided with flaring portions in the chamber within the inner dome, there being inclined shoulders on said inner dome to coöperate with said flaring portions and binding material locking the parts in position and adapted to transmit strain angularly outward through said shoulders to said body portion.
13. In insulators, a body portion having an internal supporting member, a plurality of petticoats having nested domes within said body portion, a fastening having a flaring portion in the chamber within the inner dome, there being inclined shoulders on said inner dome to coöperate with said flaring portion and binding material locking the parts in position and adapted to transmit strain angularly outward through said shoulders to said body portion.
14. In insulators, a body portion having a strengthening flange and shoulder, a petticoat having a dome mounted within the body portion and having exterior and interior coöperating shoulders, a second petticoat having a dome mounted within the dome of the first petticoat, means mounted within the second petticoat for suspending a cable or another insulator, a ring adapted to coöperate with the shoulders of the respective petticoats to transmit the strain from one petticoat to the next, and cement adapted to lock the parts together and to also transmit the strain from the suspending member within the innermost petticoat to the strengthening flange of the body portion.
15. A hanging insulator comprising a body portion formed with a shoulder, one or more petticoats nested in the body portion and having coöperating shoulders to co-act with the shoulder on the body portion, means located between the shoulders to transmit the strain from one shoulder to the complementary shoulder and means secured to the petticoat, or if more than one be used to the central petticoat, to support a cable or another insulator.
16. In insulators, the combination of a body portion having a shoulder, a petticoat having a dome mounted within the body portion, said dome being provided upon its exterior and interior with shoulders one of which is adapted to coöperate with the shoulder upon the body portion, another petticoat with a dome having exterior and interior shoulders mounted within the dome of the first petticoat, a fastening, one end of which is mounted within the dome of the innermost petticoat, and binding material adapted to permanently secure the members together and to coöperate with the respective

- shoulders on the different members to transmit strain to the shoulder upon the body portion.
17. In insulators, the combination of a body portion having a shoulder, a petticoat having a dome mounted within the body portion, said dome being provided upon its exterior and interior with shoulders coöperating with the shoulder upon the body portion, another petticoat with a dome having exterior and interior shoulders mounted within the dome of the first petticoat, a split bolt having its enlarged ends mounted within the innermost petticoat, and binding material adapted to permanently secure the members together and to lie between the ends of the split bolt and prevent its removal from the insulator and to coöperate with the respective shoulders on the different members to transmit the strain upon the bolt to the shoulder upon the body portion.
18. In insulators, a body portion, a plurality of petticoats having nested domes within said body portion, there being coöperating shoulders on said domes, a pressure member interposed between said shoulders to transmit strain between the same and binding material locking the parts in position.
19. In insulators, a body portion, a plurality of petticoats having nested members within said body portion, there being coöperating shoulders on said members, and a pressure member interposed between said shoulders to transmit strain.
20. In insulators, a body portion, a petticoat having a dome supported within said body portion, a fastening having a flaring end in the chamber within said dome, there being inclined shoulders on said dome to co-
operate with the end of said fastening, and binding material locking the parts together and adapted to transmit strain outward through said shoulders to said body portion.
21. In insulators, a body portion, a petticoat having a dome supported within said body portion, a fastening having an enlarged portion in the chamber within said dome, there being shoulders on said dome to coöperate with the enlarged portion of said fastening, and binding material locking the parts together and adapted to transmit strain angularly outward through said shoulders.
22. In insulators, a body portion, a petticoat having a dome supported within said body portion, said dome being provided with internal shoulders, a split bolt having its enlarged ends mounted within the chamber in said dome to coöperate with said shoulders, and binding material to permanently secure the members together and lie between the ends of the split bolt and prevent its removal from the insulator and to transmit strain angularly outward through said shoulders.

JOHN D. E. DUNCAN.
